Primary Examiner — T. Chase Nelson*(74) Attorney, Agent, or Firm* — Arent Fox LLP(57) **CLAIM**

The ornamental design for a sole for orthopedic boot, as shown and described.

DESCRIPTION

FIG. 1 is bottom perspective view of a sole for orthopedic boot showing our new design, according to an embodiment of the present invention;

FIG. 2 is bottom view thereof;

FIG. 3 is a left side view thereof, the right-side view is a mirror image of the left-side view;

FIG. 4 is a front view thereof; and,

FIG. 5 is a back view thereof.

The broken lines depict portions of the sole for orthopedic boot that form no part of the claimed design.
